COMBINATION DOOR CHECK AND
DOOR HOLDER

Walter Joseph Kurowski, Chicago, Ill., assignor to Aluminum Refrigerator Door Co., Inc., Chicago, Ill., a corporation of Illinois

Filed Feb. 7, 1962, Ser. No. 171,672
8 Claims. (Cl. 16—82)

This invention relates to doors, particularly refrigerator doors of the general construction disclosed and claimed in Patent No. 2,987,782, issued June 13, 1961, to Aluminum Refrigerator Door Co., Inc. on the application of Walter J. Kurowski.

One object of the present invention is to provide a new and improved door construction utilizing a combination door check and door holder, adapted to limit the opening movement of the door, and to provide a catch for holding the door open, when desired.

A further object is to provide a new and improved door construction in which the door is removable from the door frame by raising the door a short distance so as to disengage the lower hinge pin from its socket member, and in which the door is also disengaged from the door check mechanism by raising the door.

Another object is to provide a new and improved door construction having a check member which is pivotally movable with the door and is connected to the door by disengageable pin and socket elements.

A further object is to provide a new and improved door construction of the foregoing character in which the pin member is formed with a movable stop element adapted to engage a fixed stop element on the door frame, so as to limit the opening movement of the door.

Another object is to provide such a new and improved door construction in which the check member is formed with a second movable stop element adapted to be engaged by a movable catch on the frame, so that the door may be held in an open position, to facilitate free movement of materials or the like through the doorway.

Further objects and advantages of the present invention will appear from the following description, taken with the accompanying drawings, in which:

FIG. 1 is a fragmentary front elevational view showing a door construction to be described as an illustrative embodiment of the present invention.

FIG. 2 is a horizontal section, taken generally along a line 2—2 in FIG. 1, with the door in its closed position.

FIG. 3 is a view similar to FIG. 2, but with the door in its fully open position.

FIG. 4 is a view similar to FIG. 1 but showing the door in its open position, the door being shown in section.

FIG. 5 is a fragmentary vertical section, taken generally along a line 5—5 in FIG. 2.

FIG. 6 is a fragmentary vertical section, taken generally along a line 6—6 in FIG. 3.

FIG. 1 illustrates a door 10 which may be of the general construction disclosed and claimed in the previously mentioned Kurowski Patent No. 2,987,782, issued June 13, 1961. The illustrated door 10 is intended particularly for use in connection with refrigerated display cabinets of the type frequently employed in markets or the like to display dairy products or frozen foods. However, it will be understood that the invention is applicable to other types of doors. The illustrated door 10 is mounted on a frame 12 which may be secured to the display cabinet 14, a fragment of which is shown in FIG. 2. The frame 12 may extend entirely around the four edges of the door 10. It will be apparent from the drawings that the door 10 is swingable outwardly so that the customer may remove merchandise from the display cabinet.

2

The door 10 itself is bordered by a rectangular frame 16 comprising horizontal and vertical frame members 18 and 20. An insulating glass panel 22 is mounted in the frame 16. The glass panel 22 may be of the well known type having a plurality of glass panes 24 with a hermetically sealed space 26 therebetween.

Hinge means 28 are provided to mount the door 10 for swinging movement in the stationary frame 12 about a substantially vertical axis at the left-hand vertical edge of the door. Such hinge means may be of the general type disclosed and claimed in the previously mentioned Kurowski Patent No. 2,987,782, to which reference may be had for a detailed description. The hinge means 28 permit easy removal of the door 10 from the frame 12, simply by lifting the door and moving its lower end outwardly away from the frame 12. Thus, the hinge construction 28 comprises a lower hinge pin 30 (FIG. 5) which is disengageably received in a bore 32 formed in a socket member or bushing 34. In this case, the hinge pin 30 is mounted on the frame 12, while the socket member 34 is on the door 10, but this situation could be reversed. The illustrated hinge pin 30 has a lower end portion 36 which is externally threaded and is screwed into a threaded bore 38 formed in the frame 12. A wrench engaging flange 40 is formed on the hinge pin 30 above the threaded mounting portion 36. As shown, the flange 40 is hexagonal in shape. The threaded bore 38 is formed in a horizontal member 42 on the lower end of the frame 12. It will be seen that the hexagonal flange 40 engages and projects above the horizontal frame member 42.

The bushing or socket member 34 has a reduced upper portion 44 which is press fitted or otherwise secured in a bore 46 formed in a horizontal wall 48 on the lower border member 18 of the door 10. The hinge pin 30 and the bore 32 define the vertical axis about which the door 10 is swingable.

It will be evident that the socket member 34 may be disengaged from the hinge pin 30 by raising the door 10 until the lower end of the socket member clears the upper end of the hinge pin 30. The lower end of the door may then be moved outwardly away from the stationary frame 12. As explained in the Kurowski Patent No. 2,987,782, the door may then be moved downwardly to disengage the upper hinge pin from the upper socket member (not shown in the present application).

It is preferable that the door be provided with a door closer mechanism (not shown) which may comprise a spring adapted to shut the door and to hold it in a closed position. The door closer may be of the construction disclosed and claimed in the Kurowski Patent No. 2,987,782. Other suitable door closers will be known to those skilled in the art. As shown to advantage in FIG. 4, the door 10 is preferably provided with a gasket 50 which engages the stationary supporting frame 12 when the door is in its closed position, so as to form a seal between the door and the supporting frame.

The illustrated door 10 is provided with a combination door check and door closer mechanism 52 which limits the extent to which the door may be swung outwardly and also provides means whereby the door may be held in its open position, to facilitate the loading of merchandise into the display cabinet through the doorway. The illustrated mechanism 52 comprises a check plate or member 54 which is pivotally mounted on the lower horizontal wall 42 of the door frame 12, for swinging movement with the door 10. In this case, the hinge pin 30 which supports the door 10 is also employed as a pivot for the check plate 54. Thus, the check plate 54 is formed with a rather large bore 56 which is rotatably received around the hexagonal flange 40 of the hinge pin 30.

The check mechanism 52 is arranged so that it does not

interfere with the easy removal of the door 10 from the frame 12. Thus, a disengageable pin-and-socket connection 58 is provided between the door 10 and the check plate 54. In this case, a pin 60 is mounted on the door 10 and is disengageably received in a bore or socket 62 formed in the check plate 54. As shown to advantage in FIG. 5, the pin 60 may take the form of a threaded rod which extends through a bore 64 in the wall 48 and is clamped to the wall by means of upper and lower nuts 66 and 68 which are threaded onto the pin 60. It will be evident that the pin 60 is readily disengageable from the socket 62 when the door is raised.

The check plate 54 cooperates with a fixed stop 70 to limit the extent to which the door may be opened. Thus, the door may be limited to an opening movement of approximately 90 degrees. Such limitation prevents damage to the door and interference with adjacent doors. In this case, the fixed stop 70 takes the form of a screw which is connected to the stationary frame 12. The illustrated screw 70 has a threaded lower portion 72 (FIG. 5) which is screwed into a threaded bore 74 formed in a bushing 76. An externally threaded portion 78 on the bushing 76 is threaded into a bore 80 in the horizontal wall 42 of the frame 12. A hexagonal flange 82 may be provided on the lower end of the bushing 76 to engage the underside of the wall 42. It will be apparent that the bushing 76 reinforces the opening in the wall 42 and provides a firm and durable mounting for the screw 70.

It will be seen that the stop screw 70 is engageable by a movable stop element 84 on the check plate 54. In this case, the stop element 84 takes the form of an outwardly projecting member at one end of an arcuate edge 86 movable adjacent the stop screw 70. As shown, the screw 70 has an enlarged head 88 which overlaps the arcuate edge 86 so as to hold the check plate 54 against the upper side of the horizontal wall 42. At the end opposite from the stop 84, the arcuate edge 86 terminates in an outwardly projecting edge 90 which is adjacent the screw 70 when the door 10 is in its closed position.

In order that the door 10 may be held open, the mechanism 52 also comprises a movable catch 92 which is engageable with a second movable stop 94 on the check plate 54. As shown, the stop 94 takes the form of an outwardly projecting edge spaced from the stop 84 and facing in the opposite direction. The illustrated catch 92 is in the form of a lever which is swingable about a pivot screw, rivet or other fastener 95, mounted on a vertical wall portion 96 of the frame 12. As shown, the vertical wall 96 projects upwardly from the rear edge portion of the horizontal wall 42. The illustrated catch lever 92 has a downwardly projecting finger or lug 98 which is movable into engagement with the stop 94, as shown to advantage in FIG. 6. The lever 92 has an operating arm 100 with a forwardly turned grip or handle 102 thereon.

Normally, the catch lever 92 is in the position shown in FIG. 1. This normal position is shown in broken lines in FIG. 6. In this position, the operating arm 100 rests against the horizontal wall 42, while the catch finger 98 is raised above the level of the stop 94. When it is desired to latch the door 10 in its fully open position, the lever 92 is swung in a counterclockwise direction (for left hand doors and clockwise for right hand doors) into the position shown in full lines in FIG. 6. Such movement of the lever 92 moves the finger 98 into the path of the movable stop 94 so as to prevent the door from closing. Normally, the spring door closer holds the stop 94 against the finger 98 and thereby frictionally retains the lever 92 in its latching position. The lever 92 may be arranged to return by gravity to its original inactive position when the pressure between the stop 94 and the finger 98 is relieved by swinging the door to a slight extent in its opening direction.

It will be evident that the present invention provides effective means for limiting the opening movement of the door, while making provision for latching the door in its

open position. The mechanism of the present invention provides for easy removal of the door, simply by raising the door until the lower hinge pin and the lower hinge pin socket are disengaged from each other. Such lifting of the door disengages the coupling pin 60 from the socket 62 in the check plate 54. With all of its other advantages, the mechanism of the present invention is extremely compact and inexpensive to manufacture.

Various modifications, alternative constructions and equivalents may be employed without departing from the true spirit and scope of the invention, as exemplified in the foregoing description and defined in the following claims.

I claim:

1. In a combination door check and holder, the combination comprising first and second members, hinge means connecting said first member to said second member for swinging movement about a pivotal axis, a check plate swingably mounted on said second member for pivotal movement about said axis, said plate having an opening therein at a point spaced from said axis, a pin on said first member and disengageably received in said opening for swinging said plate with said first member, a fixed stop on said second member, a movable stop on said plate and engageable with said fixed stop to limit the opening movement of said door, a latching element on said plate, and a latching lever swingably mounted on said second member and having a latching member engageable with said latching element when said first member is swung into a predetermined position for holding said first member in said position.

2. In a combination door check and holder, the combination comprising first and second members, hinge means connecting said first member to said second member for swinging movement about a pivotal axis, said hinge means comprising a hinge pin on one of said members and a socket element on the other of the said members and disengageably receiving said hinge pin, said first and second members being separable by moving said first member away from said second member along said axis to withdraw said hinge pin from said socket element, a check plate swingably mounted on said second member for pivotal movement about said axis, a coupling pin disposed on said first member at a point spaced from said axis, an opening in said check plate and disengageably receiving said coupling pin, said check plate thereby being swingable with said first member, a fixed stop pin on said second member, a first movable stop element on said plate and engageable with said stop pin for limiting the swinging movement of said first member in one direction, a second movable stop element on said plate, and a lever swingably mounted on said second member and having a catch portion engageable with said second movable stop element for holding said first member in a predetermined position.

3. In a combination door check and holder, the combination comprising first and second members, hinge means mounting said first member on said second member for swinging movement about a pivotal axis, a check member mounted on said second member for pivotal movement about said axis, disengageable coupling elements on said first member and said check member for moving said check member with said first member, a fixed stop element on said second member, a first movable stop element on said check member and engageable with said first stop element for limiting the swinging movement of said first member, a second movable stop element on said check member, and a catch movably mounted on said second member for engaging said second movable stop element to hold said first member in a predetermined position.

4. In a door check, the combination comprising first and second members, hinge means disengageably connecting said first member to said second member for swinging movement about a predetermined axis, said hinge

means including disengageable pin and socket elements for connecting said members, said pin and socket elements being disengageable from each other by moving said first member away from said second member along said axis, a check member mounted on said second member for pivotal movement about said axis, second pin and socket elements connected between said first member and said check member for moving said check member with said first member, said second pin and socket elements being disengageable from each other by moving said first member away from said second member along said axis, a fixed stop element on said second member, and a movable stop element on said check member and engageable with said fixed stop element for limiting the swinging movement of said first member.

5. In a combination door check and holder, the combination comprising first and second members, hinge means disengageably connecting said first member to said second member for swinging movement about a pivotal axis, said hinge means including disengageable pin and socket elements for interconnecting said members, said pin and socket elements being disengageable from each other by moving said first member away from said second member along said axis, a check member swingably mounted on said second member for pivotal movement about said axis, second pin and socket elements connected between said first member and said check member for swinging said check member with said first member, said second pin and socket elements being disengageable from each other by moving said first member away from said second member along said axis, a fixed stop element on said second member, a movable stop element on said check member and engageable with said fixed stop element for limiting the swinging movement of said first member, and releasable catch means on said check member and said second member for holding said first member in a predetermined position.

6. In a combination door check and holder, the combination comprising first and second members, hinge means disengageably connecting said first member to said second member for swinging movement about a pivotal axis, said hinge means including disengageable pin and socket elements for interconnecting said members, said pin and socket elements being disengageable from each other by moving said first member away from said second member along said axis, a check member swingably mounted on said second member for pivotal movement about said axis, second pin and socket elements connected between said first member and said check member for swinging said check member with said first member, said second pin and socket elements being disengageable from each other by moving said first member away from said second member along said axis, a fixed stop element on said second member, a movable stop element on said check member and engageable with said fixed stop element for limiting the swinging movement of said first member, and a first movable stop element on said check member and engageable with said fixed stop element for limiting the swinging movement of said first member.

ment for limiting the swinging movement of said first member, a second movable stop element on said check member, and a catch movably mounted on said second member for engaging said second movable stop element to hold said first member in a predetermined position.

7. In a combination door check and holder, the combination comprising first and second members, hinge means connecting said first member to said second member for swinging movement about a pivotal axis, a check member swingably mounted on said second member for pivotal movement about said axis, disengageable coupling elements on said first member and said check member for swinging said check member with said first member, a fixed stop element on said second member, a movable stop element on said check member and engageable with said fixed element for limiting the swinging movement of said first member, and disengageable means on second check member and said second member for holding said first member in a predetermined position.

20. 8. In a combination door check and holder, the combination comprising first and second members, hinge means connecting said first member to said second member for swinging movement about a pivotal axis, said hinge means comprising first and second hinge elements on said first and second members, one of said hinge elements including a hinge pin and the other including a socket element disengageably receiving said hinge pin, said first and second hinge elements being disengageable from each other by moving said first member away from said second member along said axis to withdraw said hinge pin from said socket element, a check plate having a first opening received around said hinge element on said second member, said check plate thereby being swingably movable about said pivotal axis, a coupling pin projecting from said first member, a second opening in said check plate and disengageably receiving said coupling pin, said check plate thereby being swingable with said first member, a fixed stop on said second member, a first movable stop element on said plate and engageable with said fixed stop for limiting the swinging movement of said first member, a second movable stop element on said plate, and a catch movably mounted on said second member and engageable with said second movable stop element for holding said first member in a predetermined position.
